CLAIM

The ornamental design for a computer with icons in a graphical user interface, as shown and described.

DESCRIPTION

FIG. 1 is a front view of a computer with icons in a graphical user interface showing our new design; and,

FIG. 2 is a second embodiment thereof.

The longer-incremented broken-line showing a computer and the shorter-incremented broken line showing the remainder of the graphical user interface are included for the purpose of illustrating environment and form no part of the claimed design.
